(57) **CLAIM**

The ornamental design for a athletic training shoe, as shown and described.

DESCRIPTION

FIG. 1 is a top plan view of a athletic training shoe showing my new design;

FIG. 2 is a side elevational view thereof;

FIG. 3 is a bottom plan view thereof;

FIG. 4 is a rear elevational view thereof; and,

FIG. 5 is a front elevational view thereof.

The broken line showing of indicia is included for the purpose of illustrating and forms no part of the claimed design.
